[57] ABSTRACT

An electromagnetic transducer head comprises a plurality of magnetic tracking circuits with screening means between the individual circuits and in order to overcome the adverse effects of differential wear as between the magnetic circuit pole pieces and the intermediate spacer material used is made of stainless steel in place of the conventional non-magnetic materials such as brass, aluminium and plastics materials. The tracking circuits may be fitted into slots in a stainless steel blank or a blank of conventional non-magnetic material may be used with stainless steel spacers fitted in between the tracking circuits.

FIG.5.

TRANSDUCER HEAD WITH SPACER MATERIAL MADE OF STAINLESS STEEL

FIELD OF THE INVENTION

This invention relates generally to electromagnetic transducer heads, and is more particularly concerned with tape recording and/or playback heads.

DESCRIPTION OF THE PRIOR ART

In the manufacture of conventional recording/playback heads a body blank of brass, aluminium, or a suitable plastics material is grooved to hold a plurality of magnetic circuits comprising pole pieces each carrying an electrical winding. The body blank is additionally grooved between each of the grooves carrying the magnetic circuits, and into these additional grooves are fitted screens, for example of a magnetic alloy such as Mumetal. With this conventional arrangement the magnetic circuits located in their grooves are spaced from each other by land portions on the body blank, with these land portions having the screens slotted therein. This means that the magnetic circuits are bounded on each side by the material such as brass or aluminium or plastics material which constitutes the body blank.

This conventional construction has been found to have considerable disadvantages when used with magnetic tape due to the differential wear rate as between the magnetic circuit pole pieces and the intermediate spacer material such as brass, aluminium, or plastics material for example. This differential wear has the effect of causing the surface of the magnetic circuit pole pieces over which the tape moves to become concave. In addition to degrading the quality of the recording on the tape, this also causes the coating of the tape to be damaged, resulting in tape wear and the deposition of oxide particles on to the transducing head.

SUMMARY OF THE INVENTION

It is an object of the present invention to provide an improved transducing head which substantially eliminates differential wear between the magnetic circuit pole pieces and the intermediate spacing material, which reduces the overall wear rate by a factor of 5 to 10 times for example as compared with the use of conventional materials, and which also causes less damage to the associated tape resulting in a cleaner head and less tape wear.

This is achieved by using stainless steel, at least in part, as the material of the head between the individual tracking circuits over which the tape passes for the transfer of information.

Also in accordance with the present invention there is provided an electromagnetic transducer head comprising a body blank having a surface over which a tape is adapted to pass, a plurality of magnetic tracking circuits supported in said blank each with a pole piece face flush with said surface, and screening means between the respective tracking circuits, characterised in that the land areas between the tracking circuits and over which the tape is adapted to pass are at least partially of stainless steel.

This use of stainless steel has the somewhat surprising result of achieving the objects set out above and provides a greatly improved transducing head.

In one embodiment the body blank is of stainless steel and is grooved to receive said tracking circuits and screening means.

In another embodiment the body blank is of non-magnetic material and has inserts at least partially of stainless steel fitted therein between the tracking circuits.

Preferably, the land area between each pair of adjacent tracking circuits is of stainless steel adjacent to each tracking circuit with said screening means substantially midway between the tracking circuits.

A description of certain preferred embodiments in accordance with the invention will now be given by way of example and with reference to the accompanying drawings.

BRIEF DESCRIPTION OF THE DRAWINGS

FIG. 1 is a plan view of the two body parts of a single-gap recording head with a gap spacer indicated schematically therebetween;

FIG. 2 is a side view of one of the body parts of FIG. 1 taken to the line A—A of FIG. 1;

FIG. 3 is a sectional view of one of the body parts of FIG. 1 taken along the line B—B of FIG. 1;

FIG. 4 is a schematic illustration of a modified embodiment of transducing head in accordance with the invention; and,

FIG. 5 is a schematic representation of a modified form of spacer for use with the embodiment shown in FIG. 4.

DESCRIPTION OF THE PREFERRED EMBODIMENTS

FIG. 1 shows schematically the two basic body parts 35 of a recording/playback transducer head which when assembled together and secured by dowel pins and screws have a gap spacer positioned therebetween. The two body parts are indicated generally at 10 and 11, the gap spacer at 12, and an associated magnetic tape is shown at 13, the arrows indicating its direction of movement over the head. Considering the body part 10 for example, (the body part 11 is the same in construction and is therefore not separately described) this comprises a body blank which is first provided with a plurality of parallel slots 14 into which screens 16 of a magnetic alloy, such as Mumetal for example, are fitted. Wider but shallower slots 18 are then cut between each pair of screen slots 14 and receive individual magnetic tracking circuits as shown more clearly in FIGS. 50 2 and 3. The slots 14 and 18 are cut directly into the inside face 19 of the body blank.

Each of the magnetic tracking circuits comprises a pole piece 20 of a magnetic material such as Mumetal 55 having a pole tip 22 and a heel 24. Each pole piece 20 is formed by a stack of laminations and has a winding 26 formed around the central smaller cross-section portion. The coil 26 is connected to terminal pins on a terminal board 28.

In accordance with the present invention the body blank 10 (and the body blank 11 also), which has conventionally been made of brass, aluminium, or a plastics material, is made of stainless steel. The slots 14 and 18 are machined into the stainless steel body blank with the result that the pole tips 22 of the pole pieces 20 are separated by land areas 30 of stainless steel divided by the screens 16. It has been found that this replacement of the conventional materials for the lands 30 between

the tracking circuits by stainless steel has a most beneficial effect on the wear of the head, and in particular on the differential wear between the pole tips 22 and the lands 30. It also results in less damage to the tape 13 and in a reduction in the deposition of oxide particles from the tape on the head.

Although the beneficial effects obtained with the present invention are obtained with stainless steels quite generally, a stainless steel alloy of the following composition has been found particularly preferable:

Carbon—0.12%
Manganese—2%
Silicon—1%
Nickel—8 to 11%
Chromium—17 to 20%
and the remainder iron.

FIG. 4 shows an alternative embodiment of transducer head in accordance with the present invention which has the advantage as compared with the embodiment shown in FIGS. 1 to 3 that it is not necessary to machine the slots 14 and 18 in a stainless steel blank. The body blank 10 of FIG. 4 is made of brass, aluminum, a plastics material, or any other suitable easily machinable material including those which are conventionally used. Instead of machining the deep narrow grooves 14 and the relatively deep wider grooves 18 in the inside face 19 of the body blank, a rectangular cross-section portion of the blank is first removed to a depth indicated by reference numeral 40 and then a plurality of relatively shallow grooves 41 are machined in this recessed body blank. The individual magnetic tracking circuits comprising the pole pieces 20 are fitted between the grooves 41. Between the pole pieces 20 and fitted into the grooves 41 between each pair of pole pieces are spacers 46. Each of the spacers 46 is formed by the combination of a plurality of rectangular laminations of stainless steel, preferably the stainless steel alloy of the composition referred to above. In order to provide the necessary screening between the individual magnetic tracking circuits each of the spacers 46 includes a screen 48 of Mumetal for example, the screen preferably being at the centre of the spacer. The screen 48 is of the same depth and height as the spacer laminations and may have a lateral dimension transversely of the direction of movement of the tape 13 approximately equal to one third of the overall lateral thickness of the spacer 46.

FIG. 5 shows a modified form of spacer for use in an embodiment similar to that shown in FIG. 4 where, in order to accommodate the thickness of the windings 26 on the pole pieces 20 each spacer 50 comprises a Mumetal screen 52 which is provided with stainless steel spacer laminations 53 only at its ends adjacent to the pole tip 22 and heel 24 of the pole pieces.

A separate, or additional, improvement is obtained in certain configurations of magnetic circuit and spacer size ratios, by replacing a number of magnetic circuit laminations with stainless steel laminations, for example every fifth lamination of the stack.

By variations and combinations of the embodiments described above the wear rate of the parts of the magnetic transducer head can be controlled for individual circumstances of utilisation to provide desired wear characteristics.

Although the invention as described above has been given with reference to a single-gap recording/playback head it should be clearly understood that the invention

may be applied to double-gap heads and indeed quite generally to electromagnetic transducer heads of various different types.

It should also be understood that the particular relative dimensions and combinations of elements shown in the drawings and described above are not to be considered as limiting the scope of the invention. For example, although in FIG. 4 the screen 48 is shown as a plate set centrally in the spacer 46 an effective magnetic screen can be produced by other combinations of magnetic material and stainless steel laminations stacked together.

We claim:

- 15 1. A multi-track tape electromagnetic transducer head comprising a body having a surface over which a tape is adapted to pass, a plurality of respective magnetic tracking circuits supported in said body and each having a pole piece having a face flush with and forming part of said surface, each said face contacting a respective longitudinally extending area of said tape for the transfer of information between the associated magnetic and the associated area of the tape, characterised in that said surface is at least partially of stainless steel between said magnetic tracking circuits.
- 20 2. In a multi-track electromagnetic transducer head comprising a body blank having a surface over which a tape is adapted to pass in contact with said surface, a plurality of respective magnetic tracking circuits supported in said blank and each having a pole piece having a face flush with and forming part of said surface, each said face contacting a respective longitudinally extending area of said tape for the transfer of information between the associated magnetic circuit and the associated area of the tape, screening means between the respective tracking circuits, and land areas between the tracking circuits and forming parts of said surface, the improvement comprising said land areas being formed of stainless steel.
- 25 3. A transducer head as claimed in claim 2, in which the body blank is of stainless steel and is grooved to receive said tracking circuits and screening means, said land areas comprising parts of said body blank.
- 40 4. A transducer head as claimed in claim 2, in which the body blank is of non-magnetic material and has inserts at least partially of stainless steel fitted therein between the tracking circuits and forming said land areas.
- 45 5. A transducer head as claimed in claim 2, in which the land area between each pair of adjacent tracking circuits is of stainless steel adjacent to each tracking circuit with said screening means substantially midway between the tracking circuits.
- 50 6. A transducer head as claimed in claim 5, wherein the thickness of said screening means transversely of the direction of movement of the tape is substantially equal to the thickness of the stainless steel on each side thereof.
- 55 7. A transducer head as claimed in claim 4, in which each insert comprises a screening plate co-extensive with the adjacent tracking circuits and portions of stainless steel on each side of the screening plate adjacent to said pole piece faces with a gap therebelow to accommodate windings on the tracking circuit pole pieces.
- 60 8. A transducer head as claimed in claim 4, in which said stainless steel is constituted by laminations stacked together.

9. A transducer head as claimed in claim 1, in which each tracking circuit comprises a stack of laminations together forming a pole piece, with a proportion of said laminations being of stainless steel.

10. A transducer head as claimed in claim 1, in which the stainless steel has the composition:

Carbon 0.12%

Manganese 2%
Silicon 1%
Nickel 8 to 11%
Chromium 17 to 20%
and the remainder iron.
